ABSTRACT: A device for supplying liquid fuel to a burner having a high pressure air supply with a venturi section in the air supply line, and a venturi-pressure controlled fuel dosing device which includes a fuel proportioning nozzle and a membrane-operated flutter valve. One control chamber of fuel dosing device is a part of the fuel delivery conduit, and the fuel enters the air delivery conduit at the constriction portion of the venturi section.

DEVICE FOR SUPPLYING LIQUID FUEL TO BURNERS

The invention relates to a device for supplying liquid fuel to the burner of a heating appliance used in vehicles, such device may be equipped with a high-pressure blower for impelling the air for combustion, into the delivery conduit of which blower a fuel pipe opens at a point where a low-pressure zone is generated (e.g., by means of a venturi tube), and the fuel pipe may be fitted with a proportioning nozzle to effect fuel dosage.

DESCRIPTION OF THE PRIOR ART

Devices of this kind, operating with low-pressure blowers, but not incorporating a proportioning nozzle, have been described, but only in conjunction with burners of larger capacities, and even so their applicability is restricted to certain specific cases.

However, a fuel supply means similar to the above has been employed with good results for burners having smaller capacities, in which the venturi tube together with the inlet orifice of the fuel pipe is arranged in the suction conduit of the high-pressure blower, also using in conjunction therewith a membrane-equipped dosing device. This embodiment suffers from the disadvantage that the fuel must be conveyed at all times through the high-pressure blower which, on one hand, imposes restrictions with regard to the type of blower employed and, on the other hand, increases the breakdown susceptibility of the system, in that a failure of fuel admission results in the dry operation of the blower, normally lubricated by the fuel, so that disturbances occur after a relatively short time unless prevented by additional safety measures.

SUMMARY OF THE INVENTION

The object of the present invention is to provide an apparatus which, when operated with high-pressure blowers, allows the use of different types of blowers, and avoids breakdowns in case of interruptions of the fuel supply, so that no extra safety precautions are required in this respect.

To achieve the above-defined object, it is proposed according to the invention to employ in a device of the kind first mentioned a dosing device divided by a membrane into an admission and a delivery chamber, the admission chamber being situated upstreams of the nozzle when viewed in the direction of fuel flow, and the membrane controlling a valve located between the admission chamber and a fuel tank, and wherein the delivery chamber is connected with the delivery conduit of the high-pressure blower. By this last-mentioned measure the membrane control does not operate with excessively large pressure differentials, which in turn makes possible a faultless proportioning of the fuel supply and also offers further advantages in view of the consequently smaller variations of the fuel/air ratio in the case of variations in the delivery rate of the high-pressure blower.

In a preferred form of the device according to the invention, there is employed a pump connected between the membrane-controlled valve of the dosing device and the fuel-storage vessel, whose delivery automatically ceases when a predetermined pressure is reached in the pump delivery pipe, for example an electromagnetically operated diaphragm pump as described in the U.S. Pat. No. 3,267,987. Compared with a construction involving a relief valve and a return conduit, this feature is advantageous by virtue of the resulting savings in driving energy and is also preferable for constructional reasons. In any case, the important condition is to have the fuel flowing under pressure to the admission chamber of the dosing device, so as to enable the inflowing fuel to influence the pressure conditions in the delivery chamber.

According to a further preferred feature of the device in accordance with the invention, the connection of the delivery chamber of the dosing device with the delivery pipe of the high-pressure blower is provided between the latter and the inlet orifice of the fuel pipe.

BRIEF DESCRIPTION OF THE DRAWINGS

FIG. 1 is an elevated front view, partially in cutaway section, of a fuel supply device embodying the invention.

DESCRIPTION OF THE PREFERRED EMBODIMENT

The following description, referring to the accompanying drawing, discloses a preferred embodiment of the device according to the invention, and illustrates further features of the invention.

To a burner 2 comprising an ignition device 1 fuel is fed from a fuel storage container 3 through an electromagnetically operated and spring-controlled diaphragm pump 4, a dosing device 5 and a delivery pipe 6. The dosing device 5 in question comprises a venturi tube 7, a proportioning nozzle 8, a membrane 9 and a controlled fuel valve 10. The control membrane 9 divides the cavity of the dosing device 5 into an admission chamber 11 and a delivery chamber 12. The control of valve 10 is effected by a push rod 14 having a groove 13.

The air for combustion is supplied to the burner 2 by a high-pressure blower 16 driven by an electric motor 15, said blower 16 being connected with the air inlet 17 of the burner 2 by way of the delivery conduit 6, the venturi tube 7 and that portion of the delivery conduit, referenced 18, which is situated upstream of the venturi tube.

During delivery by the high-pressure blower 16, the venturi tube 7 reduces the pressure in the admission chamber 11 of the dosing device 5, which results in a downward movement of the membrane 9 and thus the opening of valve 10. Since, owing to the presence of the pressure equalizing conduit 19 extending from the delivery chamber 12 and the delivery conduit 18, no very large pressure differences occur between the admission chamber and the delivery chamber, the fuel entering under pressure through valve 10 into the admission chamber 11 effects a certain equalization of pressure and in consequence there is a return movement of the membrane 9, which again closes or almost closes the valve 10. This intensifies the low pressure created by the venturi tube 7 in the admission chamber 11, which again leads to a downward movement of membrane 9, and the consequent increased opening of the valve 10. In operation, while the membrane executes a hardly visible fluttering motion, a prearranged open position of valve 10 is established which, for a suitable coordination of proportioning nozzle 8, venturi section 7 and the output of the high-pressure blower 16, corresponds to the desired rate of fuel admission.

The pressure equalizing conduit 19 may alternatively be connected with the portion 6 of the delivery conduit, located downstream of the venturi tube 7; in general, the invention is in no way restricted to the details herein described and illustrated, but may be modified in different ways in application of the principles described.

We claim:

1. A device for supplying liquid fuel to burners, comprising: a burner inlet; an air supply means to supply combustion air at a high pressure to said burner inlet; an air delivery conduit connected between said air supply means and said burner inlet; a fuel supply means to supply liquid fuel to said burner inlet; a fuel delivery conduit connected between said fuel supply means and said burner inlet; a fuel dosing means to control the flow of fuel in said fuel delivery conduit; said fuel dosing means including a control valve means, an admission chamber, a delivery chamber, a flexible membrane means separating said admission chamber from said delivery chamber, and by its movement operating said control valve means, and a fuel proportioning nozzle; said control valve means, admission chamber, and proportioning nozzle being integral parts of said fuel supply conduit, so that the liquid fuel passes therethrough in succession;

said air delivery conduit including pressure control means to control the pressure within said admission chamber, thereby controlling the degree of opening of said control valve means; and

said fuel supply means including fuel pump means arranged upstream of said fuel dosing means and adapted to supply liquid fuel to said fuel delivery conduit at a substantially constant pressure and at a variable flow as determined by said control valve means.

2. A device for supplying liquid fuel to burners, comprising:
 a burner inlet;
 an air supply means to supply combustion air at a high pressure to said burner inlet;
 an air delivery conduit connected between said air supply means and said burner inlet;
 a fuel supply means to supply liquid fuel to said burner inlet;
 a fuel delivery conduit connected between said fuel supply means and said burner inlet;
 a fuel dosing means to control the flow of fuel in said fuel delivery conduit;
 said fuel dosing means including a control valve means, an admission chamber, a delivery chamber, a flexible membrane means separating said admission chamber from said delivery chamber, and by its movement operating said control valve means, and a fuel proportioning nozzle;

5   said control valve means, admission chamber, and proportioning nozzle being integral parts of said fuel supply conduit, so that the liquid fuel passes therethrough a succession;

10   said air delivery conduit including pressure control means to control the pressure within said admission chamber, thereby controlling the degree of opening of said control valve means; and

15   said pressure control means includes a venturi-section having a constricted portion within said air delivery conduit and a communicating conduit between said constricted portion and said admission chamber of said fuel dosing means, so as to vary the pressure within said admission chamber in accordance with the speed of air flow in said delivery conduit.

20   3. A device as claimed in claim 2, wherein said fuel delivery conduit and said air delivery conduit are joined at a point upstream of said burner inlet.

25   4. A device as claimed in claim 2, wherein said fuel delivery conduit and said air delivery conduit are joined at said constricted portion of said air delivery conduit, and wherein said communicating conduit is an integral part of said fuel delivery conduit.
